UNITED STATES PATENT OFFICE.

TRAUGOTT F. ARZT, OF WEST MANCHESTER, NEW HAMPSHIRE.

PICKER-STICK.

970,979.

Specification of Letters Patent. Patented Sept. 20, 1910.

Application filed June 23, 1909. Serial No. 503,870.

To all whom it may concern:

Be it known that I, TRAUGOTT F. ARZT, a citizen of the United States, and a resident of West Manchester, in the county of Hillsboro and State of New Hampshire, have invented an Improvement in Picker-Sticks, of which the following description, in connection with the accompanying drawings, is a specification, like letters on the drawings 10 representing like parts.

My invention relates to looms and has particular reference to means for adjusting and controlling the movement of the picker-sticks thereof.

15 In the drawing illustrating one form of my invention: Figure 1 is a side elevation of a picker-stick and adjacent parts; Fig. 2, a similar view on an enlarged scale, partly in section; and Fig. 3, a detail also on an enlarged scale to be referred to.

Referring to Figs. 1 and 2 the form of my improved picker-stick selected for illustration and description herein comprises two relatively adjustable members, an upper member 1, and a lower or foot member 2, suitably mounted in a groove 2^a of an upwardly extending arm 3 of a usual rocker 4, as by a bolt 5. The rocker 4 is adapted to oscillate upon a usual shoe 6, suitably supported at or near the axis of the lay and partaking of the movement thereof. The shoe 6 is provided with a slot 7 which registers with a slot 8 in the rocker 4 and through these slots the picker-stick depends.

35 It will be noted that the member 1 of the picker-stick terminates substantially at the shoe 6. The foot member 2 of the picker-stick, Fig. 1, is provided at its upper end with a seat 9 for the upper member 1, when required, and is also provided with the longitudinal shank 10, which is provided, in turn, at its sides with the flanges 11-11 adapted to engage said member 1 upon either side thereof, to retain it in proper vertical position. The shank 10, Figs. 1 and 3, is provided with a slot 12 to receive the bolt 5 or other suitable fastening means, for securing the members 1 and 2 in desired relation to each other and for securing the member 2 adjustably to the arm 3. The shank 10, Figs. 1 and 3, at its front face and upper end thereof is also provided with a suitable positioning member, herein a plate 13, provided in turn with a longitudinal slot 14 adapted to receive a screw 15 threaded into

the shank 10, preferably near the upper end thereof. The foregoing arrangement permits the plate 13 to be positioned at any desired point longitudinally of the shank 10 within the limits of the slot 14. This plate 13 is wider than the groove 2^a of the arm 3 so that it cannot, from any cause, drop therein. The function of this plate 13 will be shortly explained.

10 The foot member 2 is provided at its lower end with a forwardly inclined heel 16 which is, in turn, provided at either side thereof with depending ears 17-17 connected by a cross-member 18. The upper edges of these ears form shoulders 18^a upon the member 2 and, when the picker-stick is in position upon the loom, they underlie the edges 19 of the slot 7 and effectively prevent the picker-stick from jumping out of said slot when the loom is in operation.

15 The picker-stick is provided with a heel strap 20 secured herein to the lower end of the member 1 and at the front face thereof by a suitable fastening means, herein the bolt 5. The heel strap 20, Fig. 1, extends 20 downward against the inclined face 21 of the foot 2, and forward to a suitable tension device, herein a roll 22, actuated by a contained spring not shown. This tension roll is provided with a suitable means, herein 25 the thumb-screw 23, for regulating the pull thereof upon the strap 20. The cross-member 18 serves not only as an additional means to prevent the strap 20 from jumping 30 from its position between the ears 17-17, but it also serves to assist in bringing the 35 picker-stick to its position of rest at the end of the lay, as will be explained.

40 The picker-stick, Fig. 2, is adapted to be actuated by the usual lug strap 24. The lay 45 is shown at 25 partly broken away.

45 In assembling, the member 1 of the picker-stick is first seated in member 2, the flanges 11-11 of the shank 10 serving to insure its 50 correct vertical adjustment therewith. The bolt 5 is then inserted through the upright arm 3 of the rocker 4, the shank 10 of the member 2, the member 1 and the heel strap 20 and is secured in position by a nut 26, the washer 27 being positioned between said nut 55 and said member 1 if desired. After the picker-stick has been correctly positioned the positioning plate 13 is adjusted so that its 60 lower edge will rest upon the upper end of the arm 3 and the screw 15 is turned up to 65

lock said member 13 securely in position. If at any time, however, it is necessary, in order to replace the member 1 of the picker-stick, or for any other reason to loosen or remove the bolt 5 and disconnect the two members 1 and 2, such can be done without disturbing the existing adjustment of the member 2 with respect to the member 3, the positioning plate 13 holding the member 2 in position even after the bolt 5 has been removed. This convenience saves the necessity of again adjusting the member 2 relatively to member 3. The tension upon the roll 22 is now adjusted to return the picker-stick substantially to the end of the lay. Having done this it is also not only possible but convenient, by varying the adjustment of the lower heel member 2 with relation to the upper member 1 of the picker-stick and with relation to the shoe 6, as above described, to vary the backward position at rest of the picker-stick, as may be necessary, to properly cushion the shuttle in its backward movement. That is to say, by raising the foot member 2 with respect to the rocker 4 the angularity of the heel strap for a given tension of spring, will bring the picker-stick to rest at a point farther removed from the end of the slot in the lay than would be the case if said heel member were adjusted to a lower position, and since the adjustable parts at all times are readily accessible and conveniently adjustable it is possible to adjust the picker-sticks of a number of looms at any time to suit changing conditions of weather or otherwise to afford a more effective shuttle and spring action without danger of unduly pounding the parts. Angular adjustment of the picker-stick with respect to the rocker 4 may be had by means of the set screw 28 and locknut 29.

My improved picker-stick described herein is more effectively controlled in its action above referred to by means of the member 18 between the ears 17, underlying the strap 20 and before referred to. When the picker-stick moves forward the member 18 is thrown backward, away from the strap 20 but when the picker-stick, in its return movement, approaches the end of the lay the member 18 moving forward contacts with the strap 20 at its under face, and, as the movement of the picker-stick continues this member 18 presses with increasing force against said strap. The pull of the roll 22 upon the strap 20, as it returns the picker-stick, also tends to straighten said strap between the point where it leaves the surface of the roll 22 and the corresponding point upon the inclined surface 21 of the member 2 of the picker-stick, and when the return movement of the picker-stick has brought the member 18 in contact with the under side of the strap 20 the pressure of said member 18 against the under side of

the strap tends to offset any tendency of the roll 22 to return the picker-stick initially beyond the position of rest of the picker-stick and consequently tends to bring the picker-stick to a position of rest at such time as the lateral pressure of the strap 20 is equal upon the face 21 of the member 2 and cross-member 18, which is the normal position at rest of the picker-stick. 70

In order to prevent the picker-stick from jumping out of the shoe 6, which it will often do if the pull of the tension roll 22 upon the heel strap 20 is not strong enough to keep the picker-stick in position and unless the picker-stick is provided with means to keep it from jumping, it has often been necessary to increase the pull of the tension roll upon the heel strap 20 beyond what was necessary to simply return the picker-stick to the end of the lay. Such action of the roll returns the picker-stick with great force against the end of the lay and to overcome the consequent jar to the loom and to save wear and loosening of the picker it has been common to place a pad or bunt of leather or other suitable material at the end of the lay to act as a cushion for the picker-stick in its return movement. It has also been customary to secure a spring upon the side of the slot in the lay in such position that the picker-stick will contact with it in the return movement and thus be stopped before it reaches the end of the lay. 85

By the use of my improved form of picker-stick it is possible to so accurately adjust the movement of the picker-stick and the action of the roll 22 thereupon that the picker-stick will be properly returned to the end of the lay without undue force and the danger of its jumping from its seat. This cushioned stopping of the picker-stick above described reduces the inclination of the shuttle to rebound from the picker-stick, which rebound causes breaking of the filling and kinking thereof and prevents the picker-stick in its next oscillation from imparting to the shuttle its proper forward movement. The above adjustments accordingly effect an adjustment of the tension upon the heel strap to regulate the movement of the picker-stick under varying conditions and permit the movement referred to to be controlled at all times. I have ascertained that proper adjustment of the picker-stick respecting the tension roll will remove the danger of damage arising from the improper contact of the shuttle with the picker-stick and insures proper movement of the shuttle. The use of my picker-stick also obviates the necessity for using the pad or bunt now so commonly used to stop the movement of the picker-stick in the lay; removes all danger of the heel strap running off the heel of the picker-stick; the danger of the break-out from breaking of the heel 110 115 120 125 130

strap is lessened and jumping of the picker-stick is obviated.

Many things, among them the condition of the weather, which is constantly changing, have a direct influence upon the movements of the various parts of the loom and necessitate frequent adjustment thereof. My invention permits ready adjustment of the picker-stick with respect to its effective length, the angularity thereof relative to the rocker, and relative to the point of connection therewith of the strap 20 in relation to the fulcrum of the picker-stick.

Claims:

15. 1. A picker-stick for looms comprising a body member, a foot member having a shank, positioning means and alining means on said shank, a seat for the body member, a heel portion provided with ears having shoulders thereon, a connecting member for said ears and a rocker adjustably connected with the body and foot members. 70
20. 2. A picker-stick for looms comprising a body member, a foot member having a shank, positioning means and alining means on said shank, a seat for the body member, a heel portion provided with ears having shoulders thereon and a rocker adjustably connected with the body and foot members. 75
25. 3. A picker-stick for looms comprising a rocker, a body member, a foot member forming a seat for the lower end of the body member and adjustable with respect thereto and to the rocker, and positioning means for 80
30. 4. A picker-stick for looms comprising a body member, a foot member having a shank, positioning means and alining means on said shank, a seat for the body member, a heel portion provided with ears, and a rocker adjustably connected with the body and foot members. 85
35. 5. A picker-stick for looms comprising a body member, a foot member having a shank, positioning means and alining means on said shank, a seat for the body member, a heel portion provided with ears, a connecting member for said ears and a rocker adjustably connected with the body and foot members. 90
40. 6. A picker-stick member, its rocker and seat therefor, a foot member connected to the lower end of said picker-stick, said foot member being provided with positioning means and being attached to said picker-stick at one edge thereof and presenting opposed strap engaging surfaces one of which is in substantial alinement with the opposite edge of said picker stick, a heel strap and actuating means therefor. 95
45. 7. A picker-stick member, its rocker and seat therefor, a foot member connected to the lower end of said picker-stick, said foot member being attached to said picker-stick at one edge thereof, and presenting opposed 100
50. 8. A picker-stick for looms comprising two relatively longitudinally adjustable members disposed substantially in the same longitudinal plane both with respect to the direction of movement of said picker stick and laterally thereto, returning means therefor having a bearing at one end of said stick upon the outer face of one of said members, the faces of said two members being substantially alined at their adjacent ends, and positioning means for one of said members. 105
55. 9. A picker-stick for looms comprising two relatively longitudinally adjustable members, returning means therefor having a bearing at one end of said stick upon two opposed portions of one of said members and secured to the outer face of the other of said members, the faces of said two members being substantially alined at their adjacent ends. 110
60. 10. A picker-stick for looms comprising a rocker, a body member, a foot member forming a seat for the lower end of the body member and adjustable with respect thereto and to the rocker and means whereby the body member may be removed and returned to its position without disturbing the adjustment of the foot member to the rocker. 115
65. 11. A picker-stick comprising a rocker, a body member, a foot member having a seat for the lower end of said body member, an offset heel portion and provided with a shank having detachable positioning means thereon, said foot member being adjustably connected to said rocker. 120
70. 12. A picker-stick for looms comprising a rocker, a body member, a foot member forming a seat for the lower end of the body member and adjustable with respect thereto and to the rocker. 125
75. 13. A picker-stick for looms comprising a body member, a foot member having a shank, alining means thereon, a seat for the body member, a heel portion provided with ears, and a rocker adjustably connected with the body and foot members. 130
80. 14. A picker-stick for looms comprising a body member, a foot member having a shank, alining means thereon, a seat for the body member, a heel portion provided with ears having shoulders thereon, and a rocker adjustably connected with the body and foot members. 135
85. 15. A picker-stick member, its rocker and seat therefor, a foot member connected to the lower end of said picker-stick, said foot member being attached to said picker-stick at one edge thereof and presenting a strap-engaging surface in substantial alinement with the opposite edge thereof, a heel strap, and actuating means therefor. 140

16. A picker-stick for looms comprising two relatively longitudinally adjustable members, and returning means therefor having a bearing at one end of said stick upon the outer face of one of said members and secured to the outer face of the other of said members, the said faces of said two members being substantially aligned at their adjacent ends.
17. A picker-stick comprising a rocker, a body member or stick proper secured thereto, and a foot member provided with a shank adjustably connected to said rocker and with an outwardly offset heel portion that overlaps the end of said stick proper.
18. In a loom the combination of a picker-stick comprising two members disposed in juxtaposition, its rocker, a seat therefor, means to impart in and out oscillation to said picker-stick, means to vary the effective length of said stick between its fulcrum and outward oscillating means, and retaining means substantially in the line of action of said outward oscillating means to prevent jump of said stick, and opposed strap engaging portions below said retaining means.
19. In a loom the combination of a rocker member, a picker stick foot member having a shank and positioning means on said

shank to position one of said rocker and foot members relatively to the other.

20. In a loom the combination of a rocker 4, a picker stick foot member 2 having a shank 10, mounted on said rocker, a body member 1 and positioning means on said shank 10 comprising a slotted positioning member 13 and adjusting member 15 therefor to position said rocker relatively to said foot member and thereby position said foot member relative to said body member.

21. In a loom the combination of a rocker, a shoe, a picker stick foot member provided with depending ears and a strap engaging member connecting said ears.

22. In a loom a picker stick comprising a body member and a foot member therefor, said foot member provided with an inturned heel portion having opposed strap engaging surfaces thereon and a shank having positioning means for said foot member.

In testimony whereof, I have signed my name to this specification, in the presence of two subscribing witnesses.
